Primary Examiner — Sheryl Lane*Assistant Examiner* — Calvin E Vansant(74) *Attorney, Agent, or Firm* — Edell, Shapro & Finnian, LLC(57) **CLAIM**

The ornamental design for a water purifier, as shown and described.

DESCRIPTION

FIG. 1 is a bottom plan view of a water purifier.

FIG. 2 is a right side elevation view of the water purifier of FIG. 1.

FIG. 3 is a front elevation view of the water purifier of FIG. 1.

FIG. 4 is a left side elevation view of the water purifier of FIG. 1.

FIG. 5 is a rear elevation view of the water purifier of FIG. 1.

FIG. 6 is a top plan view of the water purifier of FIG. 1; and, FIG. 7 is a front, left perspective view from above of the water purifier of FIG. 1.

The broken lines depict portions of the water purifier that form no part of the claimed design.
